E. W. FUNK.
COMBINATION WRENCH.
APPLICATION FILED JULY 29, 1921.

Patented July 11, 1922.

Inventor
E. W. Funk.

By *O. Randolph, Jr.*

Attorney

UNITED STATES PATENT OFFICE.

EVERETT W. FUNK, OF COLUMBUS, OHIO.

COMBINATION WRENCH.

1,422,689.

Specification of Letters Patent. Patented July 11, 1922.

Application filed July 29, 1921. Serial No. 488,320.

To all whom it may concern:

Be it known that I, EVERETT W. FUNK, a citizen of the United States, residing at Columbus, in the county of Franklin and 5 State of Ohio, have invented certain new and useful Improvements in Combination Wrenches; and I do hereby declare the following to be a full, clear, and exact description of the invention, such as will enable 10 others skilled in the art to which it appertains to make and use the same.

This invention relates to new and useful improvements in combination wrenches and has for its primary object the provision 15 of a device for gripping nuts of different shapes and for gripping pipes and other round articles and also may be conveniently employed for pulling nails and the like.

Another object of this invention is the 20 provision of a wrench of the above stated character which will be simple, durable and efficient, and which may be manufactured and sold at a comparatively low cost.

With these and other objects in view as 25 will become more apparent as the description proceeds, the invention consists in certain novel features of construction, combination and arrangement of parts as will be hereinafter more fully described and 30 claimed.

For a complete understanding of my invention, reference is to be had to the following description and accompanying drawings, in which:—

35 Figure 1 is a side elevation of the wrench constructed in accordance with my invention.

Figure 2 is a vertical sectional view illustrating the same,

40 Figure 3 is a transverse sectional view taken on the line 3—3 of Figure 1.

Referring in detail to the drawings, the numeral 1 indicates a solid shank which has one end angularly related and bifurcated or 45 forked as illustrated at 2, to provide a nail puller. The other end of the shank 1 has formed integrally therewith stationary jaws 3 and 4 that extend oppositely to each other. The jaw 4 has a straight serrated face 5 for engaging nuts and other articles having angularly related faces while the jaw 3 is provided with an arcuate serrated face 5 to engage pipes and other round articles.

The shank 1 adjacent to the face 5 is arcuately curved as illustrated at 6 to cooperate 55 with said face 5 in engaging pipes and other round articles. The end of the shank 1 on which the jaws 3 and 4 are formed is curved as illustrated at 7.

A housing 8 is rigidly secured to the shank 60 1 by a rivet 9 and is provided with longitudinally extending openings to receive stems 10 and 11 which slidably engage the shank 1 and are provided with feed threads 12. The shank 10 has formed upon one end 65 an arcuate shaped jaw 13 provided with a serrated face to cooperate with the faces 5 and 6 for gripping pipes and other round articles. The stem 11 has formed integrally therewith a movable jaw 14 which is provided 70 with a straight face 15 that is serrated to cooperate with the jaw 4 or the face 5 thereof in gripping nuts and similar devices.

The housing 8 has journaled therein longitudinally extending adjusting nuts 16 and 75 17 which engage the feed threads of the stem 11 for the purpose of advancing and retarding the jaws 13 and 14 with respect to the jaws 3 and 4. The housing 8 is provided with openings in the top and bottom walls 80 to expose the adjusting nuts 16 and 17 whereby they may be conveniently rotated in the usual manner for operating or sliding the stems 10 and 11 to bring about adjustment of the movable jaws in respect to 85 the stationary jaws.

While I have shown and described the preferred embodiment of my invention, it will be understood that minor changes in construction, combination, and arrangement 90 of parts may be made without departing from the spirit and scope of the invention as claimed.

Having thus described my invention what I claim is:—

A wrench comprising a shank oppositely arranged stationary jaws formed on said shank and one of said jaws having an arcuate active face, and the other jaw having a straight active face, a housing secured to said shank, 100 stems having feed threads slidably received by the housing and extending parallel with the shank, movable jaws carried by said stems, and one of said jaws having an arcuate active face and the other movable jaw 105 having a straight active face, feed nuts

journalized to said housing and engaging the stems for actuating the movable jaws, said housing having cut-away portions to expose the adjusting nuts, said shank having a portion arcuately curved to cooperate with the arcuate active faces of the stationary and movable jaws.

In testimony whereof I affix my signature in presence of two witnesses.

EVERETT W. FUNK.
